United States Patent Office

Des. 222,062
Patented Sept. 28, 1971

222,062

URINAL

James L. Rutzick, St. Paul, Minn., assignor to Aquazyme
Industries, Inc., St. Paul, Minn.

Filed June 19, 1970, Ser. No. 23,574

Term of patent 14 years

Int. Cl. D23—02

U.S. Cl. D23—68

FIG. 1

FIG. 2

FIG. 3

FIG. 4

FIG. 5

FIG. 6

FIG. 1 is a front elevation of a urinal showing my new design;

FIG. 2 is a rear elevation thereof;

FIG. 3 is a left side elevation thereof;

FIG. 4 is a right side elevation thereof;

FIG. 5 is a top plan view thereof; and

FIG. 6 is a bottom plan view thereof.

I claim:

The ornamental design for a urinal, substantially as shown and described.
